UNITED STATES PATENT OFFICE.

ALFRED A. R. BERGER AND FRANK HERRMANN, OF NEW YORK, N. Y.

DESIGN FOR A SHADE-HANGER BRACKET.

SPECIFICATION forming part of Design No. 29,449, dated October 4, 1898.

Application filed July 20, 1898. Serial No. 686,456. Term of patent 14 years.

To all whom it may concern:

Be it known that we, ALFRED A. R. BERGER and FRANK HERRMANN, citizens of the United States, residing in the city of New York, county of New York, and State of New York, have invented and produced a new and original Design for Shade-Hanger Brackets, of which the following is a specification, reference being had to the accompanying drawings, in which—

Figure 1 is a perspective view of a shade-hanger bracket containing our design, and Fig. 2 is a view of one face thereof.

The leading or material feature of our design consists of a body part having an open-

ing at each side of its center and pins projecting from its lower edge and at approximately right angles therewith.

In the drawings, A designates the body, and B the pins.

Having thus described the invention, we claim—

The design for a shade-hanger bracket, substantially as herein described and shown.

ALFRED A. R. BERGER.
FRANK HERRMANN.
